UNITED STATES PATENT OFFICE.

GEORGE HALLIDAY, OF SUPERIOR, WISCONSIN, ASSIGNOR OF FORTY-FIVE ONE-HUNDREDTHS TO EDMOND JOSEPH ST. ONGE, OF SUPERIOR, WISCONSIN.

AERIAL VESSEL.

No. 873,542.

Specification of Letters Patent.

Patented Dec. 10, 1907.

Application filed May 9, 1907. Serial No. 372,662.

To all whom it may concern:

Be it known that I, GEORGE HALLIDAY, a citizen of the United States, and a resident of Superior, in the county of Douglas and 5 State of Wisconsin, have invented a new and useful Improvement in Aerial Vessels, of which the following is a full, clear, and exact description.

The purpose of the invention is to provide 10 an aerial vessel or air ship of very simple and economic construction, and which will be under the absolute and positive control of the operator, and to provide a construction capable of creating and using a cross current 15 of air with the natural air, and also to provide in connection with such construction a perpendicular centrally located sail of peculiar formation, that is a means of safety, since it is buoyant and also serves as ballast 20 to keep the boat or car in a proper position and the ship as a whole in perpendicular position.

Another purpose of the invention is to provide pivotally mounted propeller or motor wheels capable of independent and concerted adjustment, each wheel being provided with wings, and means for automatically bringing said wings in any desired number at predetermined intervals to an open 30 position at right angles to the direction of rotation, or at an acute angle to said direction of rotation, or to a closed position edge on or parallel with the direction of rotation, together with means for quickly adjusting 35 the wings with respect to the directions of rotation of the wheels, whereby the wings can be set to exert a lifting force or a descending force, or force in a lateral direction, or a combination of lateral or ascending or 40 descending forces as may be required.

A further purpose of the invention is to provide means for so mounting the said motor or propeller wheels that they may be utilized as rudders, directing the ship to the 45 right or to the left as required.

The invention consists in the novel construction and combination of the several parts as will be hereinafter fully set forth and pointed out in the claims.

Reference is to be had to the accompanying drawings forming a part of this specification, in which similar characters of reference indicate corresponding parts in all the figures.

Figure 1 is a perspective view of the im-

proved aerial vessel; Fig. 2 is a sectional plan view thereof; Fig. 3 is a central vertical section through the vessel; Fig. 4 is an enlarged sectional side elevation of one of the motor or propeller wheels and the controlling 60 and driving means therefor; Fig. 5 is a detail side elevation of a cam for controlling the position of the wings of a motor or propeller wheel; Figs. 6 and 7 are sectional plan views of the vessel drawn upon a smaller scale, 65 illustrating the manner in which the motor or propeller wheels and their supporting steering arm shear off the wind when going straight, and illustrating in dotted lines in Fig. 7 a position of the motor or propeller 70 wheel when the vessel is to be steered to the left, for example; Fig. 8 is a side elevation of the propeller or motor wheel, showing the position in which the cams are adjusted when a lifting force is required; Fig. 9 is a view 75 similar to Fig. 8, illustrating the position of the cams when a lateral force is to be exerted; Fig. 10 is a view similar to that shown in Figs. 8 and 9, but illustrating the position of the cams when a lateral force in the opposite 80 direction is to be exerted, and Fig. 11 is a sectional side elevation of one of the pivoted yokes and a section through the steering arm supporting the yoke.

A represents the basket or car of the ship. 85 This basket or car may be made of any suitable material and may be given any desired shape, but by preference it is elliptical, being more or less pointed at its forward and rear ends. The basket or car A is provided with 90 a central block 10, and centrally on this block the central portion of a steering arm B is pivoted, which arm extends out some distance beyond the ends of the car, as is particularly shown in Fig. 1.

A foot beam B' is pivoted on the steering arm B. This foot beam is of less length than the length of the car and the same bolt 11 that pivots the steering arm is utilized as a pivot for the said foot beam. This foot 100 beam B' is adapted as a support for a sail C that towers some distance above the car. The sail C is preferably made of aluminium and is of much greater fore and aft dimensions than the corresponding dimensions of 105 the car. The top 12 of the said sail C is elliptical, being widest at its center, as is shown in Fig. 3, and its ends 13 are pointed. The front and rear of the sail are made to gradually curve downward and inward and 110

the lower end 14 of the sail is very much contracted, being about the length of the foot beam B' over which it is located, and the lower end 14 of the sail is closed in any approved manner.

Stays 15 extend down from the end portions of the lower part 14 of the sail C and these stays are firmly secured in the end portions of the foot beam B'. Guy ropes 17 extend 10 down from the bottom portion of the sail C, one at each side of each stay, and these guy ropes are attached to the outer end of brace bars 16 that are secured to the said guy ropes and said guy ropes are likewise attached 15 in any approved manner to the bottom of the car A, thus insuring the sail maintaining a perpendicular position.

The sail C is divided into a number of vertical compartments 18 through the medium 20 of suitable interiorly located partitions 19, as is shown in dotted lines in Fig. 1, and these compartments are preferably filled with gas so as to render the said sail as buoyant as possible; however, the gas is not absolutely 25 necessary. In the construction of the sail the space 20 between its sides at its body portion is of uniform width, as is shown in Fig. 3, while at its upper portion the sides of the sail are inwardly and upwardly concaved, 30 as is shown at 21, meeting the edges of the top 12, whereby the top of the sail constitutes practically an aeroplane.

At each end of the steering arm B an upwardly extending yoke C² is pivoted. Each 35 yoke is provided at the upper central portion of its base with an attached or integral worm wheel 22, as is shown in Fig. 11, and the pivot pin 23 for the yoke C² extends through the worm wheel 22 thereof into the steering 40 arm, and at the upper end of each pivot pin 23 a bearing 24 is located and this bearing serves to carry a worm 25 that engages with the worm wheel 22, and each worm 25 is attached to a shaft 26 that extends in direction 45 of the car A, and each shaft 26 is provided with a hand wheel 27 within convenient reach of the occupants of the car, so that by the operation of the aforesaid worm wheels and worms either one of the yokes C² can 50 be horizontally and rotatably adjusted and held in adjustment.

A shaft 28 which in this instance is both an armature and a driving shaft, is mounted in suitable bearings in the upper ends of the 55 vertical members of each of the yokes C², as is particularly shown in Fig. 4. At one end portion of each shaft 28 an electric or other motor C' is secured, adapted to impart motion to the said shafts, and these motors are 60 connected by wires c and c' with batteries or other source of electrical supply c² located in the car A, as is best shown in Fig. 3. Each shaft 28 has a motor or propelling wheel D secured thereto, and since each wheel D and 65 the parts controlling the same is of the same

construction in each yoke, I will describe but one in detail.

The motor wheel D is provided with a peripheral flange 30 and with a hollow circular hub 29 that extends from that side of the wheel which is farthest from the motor C'. The flange 30 of the wheel D is provided with a number of apertures and through each of said apertures or corresponding apertures in the hub 29 the shanks 31 of wings E are 75 passed. In the drawings six wings are carried by each wheel D, but I desire it to be understood that any desired number may be employed. The wings E are flat and are made of aluminium or other light and strong 80 material and while their shape may be varied they are preferably formed as is shown in Fig. 4, wherein their side edges incline inward from their outer to their inner end portions. The shank 31 of each wing E is provided with a crank arm 32 at that portion of the shank that is within the hub 29, as is also best shown in Fig. 4, and each crank arm 32 has a trip pin 33 attached thereto and these trip pins pass freely out through 90 the side of the hub 29 of the wheel that is farthest from the main body of the wheel. Springs 34 are secured to the crank arms 32 of the shanks of the wings and to the side of the hub 29 through which the trip pins pass, 95 and these springs normally tend to hold the wings E at right angles to the wheel D or at right angles to the direction of rotation of the said wings.

In the operation of a wheel D it is desirable that one-third of the wings shall occupy their normal position, namely, at right angles to the direction of rotation of the wheel, and that another third, for example, shall occupy a position at an acute angle to the 100 direction of rotation, while the final third will at such time occupy a position edge on or parallel with the direction of rotation of the wheel, and it is also desirable under various circumstances or conditions of 110 flight to provide for a rapid adjustment of the controlling factor of the wheel so as to change the angularity of the wings with reference to the wheel. The change of the angularity of the wings is made to control 115 the speed and assist in steering. This is accomplished through the medium of a cam F, a cam being used in connection with each wheel D. The cam is best shown in Figs. 4 and 5, wherein its body portion is in the 120 form of a wheel having a hub 35, spokes 36 extending from the hub, and a rim 37 supported by the spokes. A flange 38 is formed upon the rim 37, extending outward at right angles to said rim, and the space 39 between the ends of the rim 37, which is segmental, represents about one-third of the circumference of the wheel, and the end portions 40 of this flange are curved outward in opposite directions extending di- 125 130

agonally across the rim 37 of the wheel, thus providing cam surfaces for the flange 38 more or less abruptly or gently curved. While the trip pins 33 connected with the shanks 31 of the wings E are in the space 39 between the ends of the flange 38 the wings will be at right angles to the path of rotation, and when the said pins are engaged by the cam faces 40 of the said flange, the wings connected with the trip pins so engaging are turned at an acute angle to the direction of rotation, while the wings whose trip pins 33 engage with the plain face of the flange 38 will be brought practically edge on or parallel with the direction of rotation, but the angularity of these wings with reference to the wheel D is controlled by the movement of the cam F to and from the hub of the wheel D. In moving the cam closer to the said hub 29 the angularity is less pronounced or more acute, and when the cam is moved away from the said hub the angularity of the wings is more pronounced. The cam wheel F is secured to a sleeve 41, and this sleeve is loosely mounted on the shaft 28 and the sleeve 41 extends through a bearing for the shaft 28 and likewise through an auxiliary bracket bar 42 at the outer side of the yoke C² opposite that at which the motor C' is located, as is also shown in Fig. 4. A hollow drum 43 is loosely mounted on the said sleeve 41 between the bearing for the shaft 28 and the cam wheel F. The open portion of the drum is that which faces the cam wheel, and the flange or peripheral portion of the drum is provided with transverse or diagonal slots 44 that receive the spokes 36 of the cam wheel F, permitting the said cam wheel to be adjusted to or from the motor or propelling wheel D. The rotary adjustment of the cam wheel F is obtained by securing a worm wheel 45 to the outer face of the drum 43 and providing a worm 46 for engagement with the lower portion of the worm wheel, the shaft 47 of the worm being made to extend inward in direction of the car terminating in a suitable hand wheel, as is shown in Fig. 1, and likewise in Fig. 2, and the bearings for the shaft 47 are located at the inner side face of the yoke C², so that the drum 43 is prevented from shifting until the worm wheel 45 is revolved, and by turning the shaft 47 the drum can be revolved in a forward and in a rearward direction carrying the cam wheel F with it. With reference to the lateral adjustment of the said cam wheel, this is effected by providing an exterior thread on the outer end portion of the sleeve 41 to which the cam wheel is secured and locating a nut 48 on the threaded portion of the sleeve between the two bearings therefor, and providing the said nut with a wheel-like rim whereby the nut may be readily turned to

cause the sleeve 41 to move inward or outward carrying the cam wheel F with it.

The steering arm B may be moved so as to assume reverse diagonal positions relatively to the hull of the vessel, as is shown in Figs. 6 and 7 for steering purposes, by means of a tiller 49 that is attached to the said steering arm B, preferably at its central portion.

It will be observed that each of the motor or propelling wheels can be independently 75 rotatably adjusted independent of the steering arm B', and that they can be collectively adjusted or carried to any desired lateral position for steering purposes, the adjustment of the said steering arm B, as is shown 80 in dotted lines in Fig. 7, and it is also evident that the wings E on said wheels D can be made to automatically assume different positions in groups according to conditions. If, for example, it is desired to place the 85 wings of the arms in position for action to produce an ascending or lifting force, the cam wheels F are turned until the open portions 39 of their cam surfaces are at the front lower third portion of the wheel, as is shown 90 in Fig. 8. Should it be desirable to cause the wings to act so as to create a lateral force the cam wheels F are adjusted so that the space between the cam surfaces 40 will be at the bottom portion of the wheel, as is shown 95 in Fig. 9. When it is desired to cause the wings to act to create a lateral force in opposite direction to that shown in Fig. 9, the cam wheels F are turned so as to bring their open space 39 uppermost, as is shown in Fig. 100 10. If it is desired to create a forward and lateral force at the same time, the cam wheels are so placed as to present open wings at the lower third of the wheel, the other two-thirds of the wings through the lateral 105 movement of the cams being made to assume an angle of about 35°, and so on by adjustments of the cams or wings of the propeller or motor wheels will occur a force in different directions, and by operating the said wheels 110 D force may be applied in any required direction, thus insuring absolute and positive control of the machine at all times; and it is evident that all of the adjusting mediums are within convenient reach of the occupants of 115 the car and may be quickly brought into action.

Having thus described my invention, I claim as new and desire to secure by Letters Patent,—

120

1. In aerial vessels, a car, a sail from which the car is suspended, which sail is provided with an elliptical top constituting practically an aeroplane, a longitudinal reduced centrally located bottom and substantially 125 straight side surfaces extending from a point between its top to its bottom, a steering arm pivoted on the car, propeller or motor wheels carried by the steering arm, means for rotating the said wheels, and means for shifting 130

the steering arm whereby the wheels serve as rudders for the ship.

2. In aerial vessels, a car, a gas containing sail from which the car is suspended, which sail is provided with an elliptical top constituting practically an aeroplane, a longitudinal reduced centrally located bottom and substantially straight side surfaces extending from a point between its top to its bottom, a steering arm fulcrumed upon the car, and combined steering and propelling devices carried by the said arm.

3. In aerial vessels, a sail constructed of light, thin metal having an elliptical top, a contracted bottom, and a body portion reduced in thickness below the elliptical top, partitions within the sail dividing the same into compartments, a car suspended from the sail, and combined steering and propelling devices adjustably mounted with reference to the car.

4. The combination with a vertical gas containing sail having an elliptical top constituting practically an aeroplane, and a car suspended from the said sail, which sail tends to maintain the car in perpendicular position, of a steering arm pivotally supported upon the car, a combined propelling and steering wheel rotatably adjustable at each side of the fulcrum of the said steering arm, driving mechanisms for the wheel, and means for swinging the steering arm to the right or to the left to direct the ship in the required direction.

35. 5. In an aerial vessel, a perpendicularly located sail adapted to be charged with gas, a car suspended from the sail, a steering arm pivoted upon the car, bearings carried by said arm, devices for rotating said bearings and holding them in adjusted position, a wheel carried by each bearing, wings pivoted at the periphery of the wheels, mechanism for changing the angularity of the wings from a position at right angles to the direction of rotation to intermediate diagonal positions, including a position parallel with the direction of rotation of the wheel, a tiller for the steering arm, and motors connected with the shafts of the said wheels.

50. 6. In an aerial vessel, the combination with a perpendicularly located sail having compartments therein capable of receiving a sustaining fluid, a car suspended from the same, a steering arm pivoted upon the car, and a tiller for said arm, of bearings rotatably mounted upon said steering arm, means for adjusting the bearings and holding them in adjusted positions, a shaft mounted in each bearing, driving mechanisms for the said shafts, wings at the peripheral surface of the wheel, pivotal mounts for the wings, cam devices carried by the bearings, and connections between the cam devices and the wheels, which connections serve to automatically change the position of the wings

relatively to the peripheral portions of the wheel, during the rotation of the latter from a point at right angles to the direction of rotation to a position parallel with said direction of rotation.

7. In an aerial vessel, the combination with a perpendicularly located sail having compartments therein capable of receiving a sustaining fluid, a car suspended from the same, a steering arm pivoted upon the car, and a tiller for said arm, of bearings rotatably mounted upon said steering arm, means for adjusting the bearings and holding them in adjusted positions, a shaft mounted in each bearing, driving mechanisms for the said shafts, a wheel for each shaft, wings at the peripheral surface of the wheel, pivotal mounts for the wings, cam devices carried by the bearings, and connections between the cam devices and the wheels, which connections serve to automatically change the position of the wings relatively to the peripheral portions of the wheel, during the rotation of the latter from a point at right angles to the direction of rotation to a position parallel with said direction of rotation, and means for rotating the cams to a desired position and holding said cams in such position, means for laterally adjusting the said cams to and from the wheels and holding them in lateral adjustment, whereby to increase or decrease the degree of angularity of the wings and to cause the change to take place at predetermined points in the rotation of the wheels.

8. In aerial vessels, a car, means for suspending the same, a steering arm carried by the said car, a tiller therefor, a combined propelling and steering wheel adjustably mounted upon the said steering arm, wings at the periphery of said wheel, spring-controlled pivotal mounts for the wings, trip pins extending from the mounts, and a cam mounted for rotary adjustment and adjustment to and from the wheel in the path of the said trip pins, and independent devices for effecting the two said adjustments of the cam.

9. In an aerial vessel, a bearing, a support therefor, means for rotating the bearing upon its support and holding it in adjusted position, a shaft mounted to revolve in the bearing, a propeller wheel secured to the shaft, wings at the periphery of the wheel, tension-controlled pivotal mounts for the wings, trip devices extending out over said mounts, adapted to assist in changing the position of the wings, a cam loosely mounted on the shaft in the path of the said trip devices, means for imparting rotary adjustment to the cam, and also means for adjusting the said cam to and from the said wheel.

10. In aerial vessels, a propelling device therefor, consisting of a shaft, a support for the same, a wheel secured to the shaft, wings at the periphery of the wheel, mounts for the

wings pivoted in said wheels, trips for the mounts extending out from the wheel, a cam loose upon the shaft and located in the path of the said trips, means for imparting rotary 5 adjustment to the cam, and independent means for giving the cam lateral adjustment, whereby during the revolution of the wheel to change the position of the wings relatively to the direction of rotation of the 10 wheel.

11. In an aerial vessel, bearings, a support for the bearings, means for adjusting the bearings on their support in the rotary direction, a shaft mounted to turn in the said bearings, a motor connected with the said shaft, a propeller wheel secured to the shaft, wings located at the periphery of the propeller wheel, mounts for the said wings, pivoted in the periphery of the wheel and terminating 15 at their lower ends in spring-controlled 20 cranks, trip pins connected with the said

cranks and extending out from the wheel, a cam wheel loosely mounted on the said shaft, being rotatable and laterally adjustable, the said cam wheel being provided with a cam 25 surface consisting of a segmental marginal flange to be engaged by the trip pins, the said flange having its end portions outwardly curved in opposite directions extending diagonally over the rim of the cam wheel, 30 the remaining portions of the said flange being straight, and independent means for imparting said rotary adjustment to the cam wheel and said lateral adjustment.

In testimony whereof I have signed my 35 name to this specification in the presence of two subscribing witnesses.

GEORGE HALLIDAY.
